UNITED STATES PATENT OFFICE.

LEONIDAS BAXTER, OF DAYTON, OHIO, ASSIGNOR TO THE THOMAS MANUFACTURING COMPANY, OF DAYTON, OHIO, A CORPORATION OF OHIO.

DESIGN FOR A COMBINATION BURNER AND SHADE-HOLDER FOR HYDROCARBON-LAMPS.

46,891.

Specification for Design.

Patented Feb. 2, 1915.

Application filed October 15, 1914. Serial No. 866,867. Term of patent 14 years.

To all whom it may concern:

Be it known that I, LEONIDAS BAXTER, a citizen of the United States, residing at Dayton, in the county of Montgomery and State of Ohio, have invented a new, original, and ornamental Design for a Combination Burner and Shade-Holder for Hydrocarbon-Lamps, of which the following is a specification, reference being had to the accompanying drawing, forming part thereof.

The figures are a side elevation and top

plan view of a combination burner and shade holder for hydrocarbon lamps, showing my new design.

I claim:

The ornamental design for a combination burner and shade holder for hydrocarbon lamps, as shown.

LEONIDAS BAXTER.
